UNITED STATES PATENT OFFICE.

EARL W. NEWTON, OF CHICAGO, ILLINOIS.

DESIGN FOR A CUP OR SIMILAR ARTICLE.

Application filed May 31, 1923. Serial No. 6,365. Term of patent 7 years.

To all whom it may concern:

Be it known that I, EARL W. NEWTON, a citizen of the United States, residing at Chicago, in the county of Cook and State of Illinois, have invented a new, original, and ornamental Design for Cup or Similar Article, of which the following is a specification, reference being had to the accompanying drawing, forming part thereof.

The figure is a perspective view of a cup, showing my new design.

I claim:

The ornamental design for a cup or similar article, as shown.

EARL W. NEWTON,
